CLAIM

The ornamental design for a packaging for tobacco, cigarette papers and cigarette filters, as shown and described.

DESCRIPTION

1.-2. Packagings for tobacco, cigarette papers and cigarette filters

1.1 is a top plan view shown in open configuration.

1.2 is a perspective view shown in a closed configuration.

1.3 is an end perspective view shown in open configuration.

1.4 is an opposite end perspective view shown in open configuration.

1.5 is a front perspective view shown in open configuration.

1.6 is a rear perspective view shown in open configuration.

2.1 is a top plan view shown in open configuration.

2.2 is a perspective view shown in a closed configuration.

2.3 is an end perspective view shown in open configuration.

2.4 is an opposite end perspective view shown in open configuration.

2.5 is a front perspective view shown in open configuration.

2.6 is a rear perspective view shown in open configuration.
